METHOD OF REDUCING THE OCTANE DEMAND OF ENGINES

Everett C. Hughes, Shaker Heights, Ohio, assignor to The Standard Oil Company, Cleveland, Ohio, a corporation of Ohio

No Drawing. Application September 12, 1952,
Serial No. 309,359

10 Claims. (Cl. 123—1)

The present invention relates to a method of reducing the octane demand of a dirty internal combustion engine by removing deposits from the surfaces of the combustion chamber or chambers thereof in a simple, safe and effective manner that does not require dismantling of the engine.

It is well known that deposits quickly accumulate in the combustion chambers of internal combustion engines such as those used in automobiles. An engine with deposits requires the use of a gasoline with a higher octane rating than does a clean engine if the engine is not to knock, and the dirty engine is said to have a higher octane demand. This becomes apparent to the driver of an old automobile by the knocking of the engine while accelerating, climbing a hill or otherwise operating the engine under greater than normal load. The deleterious effects of such accumulations of deposits are particularly noticeable in engines having a high compression ratio because the margin between the octane number of gasolines on the market and the octane demand of the engine when clean is narrower than for engines having lower compression ratios.

A great number of methods have been proposed heretofore for cleaning the combustion chambers of an internal combustion engine. One of these methods is that of introducing a liquid solvent into the carburetor while the engine is running. Although this method produces great billows of smoke at the exhaust, it has been found, upon taking an engine so treated apart after the operation, that little of the deposits are actually removed.

Another of these methods described in prior patents is that of inserting metal objects such as chains and the like into the various cylinders through the spark plug holes, replacing the spark plugs, running the engine, and then removing the chains or other similar objects. This method of operation has been found entirely impracticable because (a) these objects generally are so hard and non-crushable as to cause injury to the engine if jammed between moving parts such as a valve head; (b) the number of particles introduced into each cylinder at one time is either so great as to interfere seriously with the combustion and the movement of the valves and piston, or so small that the spark plug for each cylinder will have to be removed and replaced so often during a single cleansing as to make excessive the time required for the operation and the probability of injury to the spark plugs; (c) many of the particles roll out through the valves before the engine gains sufficient speed to make them effective, thus resulting in a waste of particles and in an accumulation thereof in the exhaust manifold and muffler; and (d) the noise of the operation has caused some concern on the part of consumers, and for the further reason that consumers would object to having metal particles placed in the combustion chambers of their engines.

In view of the failure of the many methods proposed in prior patents of which the foregoing are but a few, it is still standard practice to clean an internal combustion engine by removing the head and grinding the deposits away from the tops of the pistons and valves and the recesses in the cylinder head forming the confining surfaces of the combustion chamber. This method is expensive and time consuming and renders the engine useless for at least a day.

A method for removing the deposits in the combustion chambers of an internal combustion engine has now been found that does not require a lifting of the cyl-

2

inder head, is not injurious to the engine, is extremely inexpensive and requires very little time. In essence, this method involves introducing into the combustion chamber of an engine a plurality of discrete particles essentially comprising graphite, and running the engine with said particles in the combustion chamber to remove the deposits.

Because of the relative fragility and low specific gravity of particles essentially and primarily comprising graphite, there is practically no limit to the size of the individual particles that may be used in accordance with the method of this invention, provided they can be introduced in the manner described hereinafter. Even if the particles, or some of them, have a dimension larger than the minimum clearance in the combustion chamber between the piston and the cylinder head, or if any of said particles should be jammed between any relatively moving metal surfaces, such as for example a valve and a valve seat, such particles would be crushed without damage to the metal surfaces. There is also no limit to the shape that the particles may have. Thus, for example, they may be cubes, cylinders, ellipsoids, spheres and the like. One shape that has been found to be particularly effective and suitable, primarily because it is the shape in which graphite particles are most readily available, is the cylinder. The particles preferred for the purposes of the present invention are cylinders essentially comprising graphite and having a diameter of about $\frac{1}{8}$ " and lengths ranging from about $\frac{1}{8}$ " to about $\frac{3}{16}$ ".

The hardness of the particles is not critical, however, harder graphite particles are more effective because they are not pulverized as quickly in the combustion chambers. Some desirable effects in reducing octane demand are obtained with graphite pellets that are as soft as the graphite of a No. 1 "lead" pencil. The hardest known graphite particles have been tested and found to be effective without in any sense causing injury to the engine.

The particles may consist entirely or primarily of graphite. They may, and desirably do, contain, in addition to the graphite, such binders as coal tar pitch, synthetic resins, clay, sodium silicate, borax, lead and the like. One type of particle that has been found entirely suitable is prepared by heating petroleum coke to drive off volatile matter, grinding it to a powder form and mixing it with sufficient coal tar pitch to make the composition plastic enough for extrusion. Thereafter rods of approximately 1 ft. in length and about $\frac{1}{8}$ " in diameter are extruded, baked at a high temperature of the order of 1000 to 2500° C. and then cut to lengths of approximately $\frac{1}{8}$ " to $\frac{3}{16}$ ".

The term "non-liquid, non-powder form" as used in the claims is intended to distinguish the discrete particles used in practicing the invention from graphite in a colloidal or similar liquid form and from powdered graphite.

The method of the invention is most effectively carried out by introducing the particles into the engine through the carburetor, with the air filter removed, and the intake manifold for distribution among the engine cylinders. This is accomplished by pouring the particles in a steady stream in fairly uniform increments into the carburetor past the butterfly valve while the engine is run at a fairly high speed. The method is preferably carried out in such a manner that approximately 75 to 300 particles per cylinder are introduced within approximately 1 to 10 minutes or at an overall rate of between about 7.5 and 60 particles per minute per cylinder. The rate and amount should not be so great as to cause the engine to stop during the cleaning operation.

The introduction of the particles can be accomplished by means of a suitable dispenser or by the continual addition of pinches of say about 5 to 40 particles each.

The advantages of this method of cleaning an internal combustion engine are numerous. The method is extremely simple and may be carried out in less time than it takes to have the oil changed. As shown in the examples hereinafter, the method is effective in reducing as much as 65% of the octane requirement increase of a dirty engine and in increasing its power output

by as much as 15%. It does not require a lifting of the cylinder head and the preferred embodiment of the method does not even require the removal of the spark plugs. The method does not alarm the customer because it is not noisy and it is a matter of common knowledge among customers that graphite has lubricating value. The method is not at all harmful to the engine but in fact lubricates the engine parts. In addition to its many desirable effects, the most apparent of which is the reduction in octane requirement and increase in power output of the engine, the method also appears to have desirable effect of reducing the rate at which the octane requirement of the engine will increase after normal operation is resumed. Finally, but by no means least important, the method has the advantage of utilizing particles of a material that is not critical, as are lead, copper and other metals, in time of war or national emergency.

These and other advantages, as well as the utility of the method of this invention, will become more apparent from the following examples, it being understood that these examples are illustrative only and not limitative of the scope of the invention.

Example 1

A standard Chevrolet passenger car engine was run on a test stand for 109 hours (equivalent to about 4360 miles at a conversion of 40 miles per hour) during which the octane requirement of the engine increased from 74 to 85. At the end of that time approximately 1500 graphite particles, made from petroleum coke and coal tar pitch, extruded, baked and cut as previously described, and having a diameter of about $\frac{1}{8}$ " and lengths ranging from about $\frac{1}{8}$ " to $\frac{3}{16}$ ", were introduced within an interval of about 5 minutes on each side of the butterfly valve in the throat of the carburetor. It was found that this treatment reduced the octane requirement of the engine by 4 and increased the power output by 2.3%.

The engine was then run for an additional 111 hours, during which time the octane requirement increased, at a slower rate than in the first part of the run, from 81 to 87. At the end of that time the test treatment with graphite particles was repeated and it was found that the octane requirement of the engine was reduced by 9 and that the power output was increased by 15%. The engine was then run for an additional 120 hours. It was found that in this part of the run the treatment had also reduced the rate of octane requirement increase. Upon subsequent dismantling of the engine, careful inspection showed that no harm had been done to any of the parts.

Comparison of the rate of increase of octane requirement before the first treatment with the rate of increase after the first and second treatments with graphite particles, demonstrates the lasting effect of the treatment in reducing the rate at which the octane requirement increases with further operation.

Example 2

A total of five tests were carried out with standard Chevrolet passenger car engines. Each test was begun with a clean engine whose octane requirement was determined. Each engine was then run until its octane requirement ceased to increase further to any appreciable degree. The octane requirement increase of the engine and its brake horsepower were then determined. Thereupon, approximately 1500 graphite particles were introduced in the same manner as described in Example 1, following which the octane requirement and the brake horsepower of the engine were determined by standard means. The results are tabulated in Table I immediately below:

Table I

Run No.	1	2	3	4	5
Octane Requirement Increase	11	8	12.5	11	11.5
Reduction in Octane Requirement due to cleaning	3	3	5.5	6	7.5
Percent Power Increase	4	2	3	11	3

The results in tests Nos. 4 and 5, which are superior to those obtained in tests Nos. 1, 2 and 3, are believed due

to the fact that in those tests graphite particles were used which are harder than those used in tests Nos. 1, 2 and 3. These harder particles are the hardest developed lately and available from the National Carbon Division of the Union Carbon and Carbide Corporation.

Test No. 5 shows that the method of the invention is capable of reducing the octane requirement by 65% of the possible reduction and the results of test No. 4 indicate that the power output may be increased by as much as 11%.

The method described above was further evaluated in a series of standard cars of various makes indicated in the first column of the following table, which had been driven for the number of miles indicated in the second column of the table. The octane requirement of each car before being treated in accordance with the invention was measured and this is indicated in the third column. Each car was then cleaned utilizing the graphite pellets in the manner described heretofore. The octane requirement of each car was measured after the cleaning and this is indicated in the fourth column. The octane requirement reduction is indicated in the fifth column. The per cent power increase at 15 to 35 miles per hour acceleration was also determined before and after the cleaning method of the invention and the percentage increase is indicated in the last column of the following table:

Table II

Car Type	Mileage	Octane Requirement Before	Octane Requirement After	Octane Requirement Reduction	Percent Power Increase at 15-35 M. P. H. Acceleration
Chevrolet-1948	31,443	87	83	4	5.5
Plymouth-1948	23,002	79	75	4	3.5

¹ Not measured.

It is apparent that many variations and modifications will occur to those skilled in the art upon reading the foregoing description. All those variations and modifications are intended to be included within the scope of this invention as defined in the appended claims.

I claim:

1. A method of reducing the octane requirement of a dirty internal combustion engine which comprises introducing into the combustion chamber of an engine, a plurality of discrete particles in non-liquid, non-powder form, essentially comprising graphite, and running the engine with said particles in the combustion chamber to remove deposits therefrom.

2. The method of claim 1 in which the particles are introduced through the intake manifold of the engine for conveyance to the engine cylinders while the engine is running.

3. The method defined in claim 2 wherein the discrete particles are introduced into the intake manifold through the throat of the carburetor.

4. The method defined in claim 2 wherein the number of particles introduced is between about 75 and 300 per cylinder.

5. The method defined in claim 2 wherein the discrete particles are particles of synthetic graphite.

6. The method defined in claim 2 wherein the discrete particles are in the form of small pellets.

7. The method defined in claim 2 wherein the discrete particles are cylinders having a diameter of about $\frac{1}{8}$ " and lengths of approximately $\frac{1}{8}$ " to $\frac{3}{16}$ ".

8. A method of operating a dirty internal combustion engine to reduce the octane requirement thereof normally resulting from operation of such an engine, which comprises introducing into a combustion chamber of said

engine a fuel charge and a charge of discrete particles in non-liquid, non-powder form, essentially comprising graphite.

9. The method defined in claim 8 wherein the discrete particles are introduced into the intake manifold through the throat of the carburetor.

10. The method defined in claim 8 wherein the number of particles introduced is between about 75 and 300 per cylinder.
